UNITED STATES PATENT OFFICE

EDWARD G. HOCH AND JOHN A. LEVERING, OF MINNEAPOLIS, MINNESOTA, ASSIGNEES
TO KOZEKAE, INC., OF MINNEAPOLIS, MINNESOTA, A CORPORATION OF MINNESOTA

BABY BASKET AND SUPPORT

Application filed March 15, 1929. Serial No. 347,289.

Our invention relates particularly to baby carriages of the type wherein both the running gear and the basket-like body are capable of being collapsed or folded in flat formation for the more convenient handling, carrying or storage, and generally stated, the invention consists of the novel devices, combinations of devices and arrangement of parts hereinafter described and defined in the claims. A baby carriage of the character just above referred to is disclosed and broadly claimed in United States Patent No. 1,596,283, of August 17, 1926, entitled "Folding baby carriage" granted to Julius A. Mahr. A basket-like body such as disclosed in the said prior Mahr patent is capable of being carried by the running gear of the baby carriage or to be hung as a hammock from suitable supports on an automobile, but if removed from both of the above noted types of supports and set upon the floor, the body or basket would collapse and, moreover, its bottom, which is flexible as well as its walls, its walls being usually made of canvas, would rest upon the floor.

The present invention improves the construction of the collapsible basket or body and provides a basket which while capable of being collapsed or folded flat, when desired, will normally be held against collapsing or folding even when set upon a floor and when so set upon a floor or similar support, will have its flexible bottom properly suspended above the floor so that it will afford a cushion base for carrying the baby or child.

In the accompanying drawings, which illustrate the invention in its present commercial form, like characters indicate like parts throughout the several views.

Referring to the drawings:

Fig. 1 is a perspective showing the improved basket or body supported by a collapsible running gear such as that disclosed in the prior Mahr patent, above identified;

Fig. 2 is a perspective showing the basket removed from the running gear and set upon the floor, some parts being broken away;

Fig. 3 is an enlarged fragmentary section taken on the line 3—3 of Fig. 2;

Fig. 4 is a perspective showing the foldable basket-supporting base removed from the basket;

Fig. 5 is a fragmentary horizontal section taken approximately on the line 5—5 of Fig. 1, looking upward;

Fig. 6 is a section taken on the irregular line 6—6 of Fig. 5, the said parts being turned right side up;

Fig. 7 is a fragmentary end view showing parts found in the vicinity of the line marked 7—7 on Fig. 2;

Fig. 8 is a plan view of one of the upper spreader rim sections of the collapsible basket; and

Fig. 9 is a view corresponding to Fig. 8, but illustrating a slightly modified construction.

The folding running gear here illustrated and which is substantially like that of the prior Mahr patent above identified, includes a reach 10, a pair of posts 11, a pair of couplings 12, and two pairs of radius rods 13, the outer ends of each pair being bent outwardly into axial alignment to afford stub axles on which the wheels 14 are journaled. The radius rods 13 are foldably connected by toggles 15. At their upper ends, the posts 11 are provided with handles 16 and with upstanding hanger hooks 17.

For the purpose of this case, it is not necessary to further trace the operation or detail construction of the running gear proper for the same is fully disclosed in said prior Mahr patent and, moreover, the present invention is not limited to any specific form of running gear. It may, however, be stated that when out of use, the wheels of the running gear may be folded together substantially in the plane of the reach 10 and the posts 11 can be turned over into the longitudinal zone of the reach, thereby forming a very compact close structure.

The body of the basket or collapsible body is preferably made of canvas, drilling or other suitable fabric, the side-forming portion of which is indicated by the numeral 18 and the bottom portion of which is indicated by the numeral 19. The bottom 19 is held in a spread out condition by a marginal spreader

80

85

90

95

100

rod 20, preferably set into a hem formed therein. The upper edge of the side-forming canvas 18 is formed with a hem 21 into the curved end portions of which is inserted a U-shaped spreader rod 22. The lower rod 20 affords a continuous bottom spreader rim while the two U-shaped rods 22 afford an upper sectional spreader rim and give lateral flexibility to the upper side portions of the basket. When otherwise unsupported, the basket may be collapsed and folded flatwise by pressing together the upper and lower spreader rims.

As a means for supporting the basket from the hooks 17 of the running gear post, there is provided a pair of coupling links 23, the outer ends of which are perforated to engage with the hooks 17 and the inner ends of which are formed with hooks 24 that are detachably engageable with portions of the spreader rim sections 22 that are exposed at the extreme ends of the basket by cutting away portions of the canvas side walls 18, as shown at 18^a. To prevent lateral slipping of the hooks 24 on the rods or sections 22 the latter are preferably formed with ribs 22^a and the hooks 24 are bifurcated at 24^a to straddle said flanges.

As an important feature of this invention, there is provided a detachable basket-supporting base, the preferred form of which is illustrated in the drawings, see particularly Fig. 4. This base comprises a marginal base rim preferably formed from a quite stiff but resilient steel rod 25 bent into oblong formation and provided at the extremes of the oblong with upstanding U-shaped abutments 26. Adjacent the abutments 26, basket-supporting standards are foldably applied to the supporting base 25. These standards, as shown, are formed each from a pair of rods 27 rigidly connected at their intermediate portions, but pivotally connected at the lower ends of their prongs to the supporting base 25 by loops 28 located close to the respective abutments 26. At their upper ends of the prongs, the standards 27 are formed with outturned hooks 29 that are engageable with the exposed portions of the upper spreader rim sections 22, as best shown in Figs. 2 and 5.

The preferred arrangement of the parts just described is as follows:

Normally, the substantially parallel sides of the base 25 are slightly bowed upward and the standards 27 when turned against the abutments 26 will be spread at their upper ends considerably farther apart than the distance between the two exposed portions of the upper spreader rim sections 22. For the application of the hooks 29 to the exposed portions of said rim sections 22, the standards 27 by being forced against the abutments 26 may be moved toward each other far enough to permit the engagement of their hooks 29 with the exposed portions of the rim sections 22. When the standards are thus interlocked

to the rim sections 22, they will be held in such interlocking engagement by a very considerable spring tension produced partly by springing of the standards themselves, but chiefly by springing downward of the intermediate portions of the sides of the base 25. When the standards are applied as just described, the sides of the base 25 will be bent for substantially flat or continuous contact with the floor or flat surface, which is the usual desired arrangement, but, of course, the downward springing of the sides of the base 25 could be increased to such an extent that they would afford rockers permitting endwise rocking movement of the basket on the floor. When the supporting base is applied to the basket, the basket with the base can be removed from all suspending supports and set upon the floor and the base will then support the basket with its flexible bottom well above the floor. To add to the appearance of the basket when thus used, it is shown as provided with a depending skirt 30 which, as shown, has loose flaps 31 adapted to be buttoned or fastened around the lower portions of the applied standards 27. The applied standards not only support the basket above the floor, but positively hold the top and bottom portions of the basket extended vertically so that the basket cannot be collapsed.

When the basket is to be collapsed or folded, the standards 27 are detached and turned into the plane of the base 25 by outward pivotal movement, as shown by dotted lines in Fig. 4, and then, of course, the basket can be collapsed into the flat formation. The bottom of the basket may be applied with straps 32 and 33 for connection, respectively, to the reach 10 and to the base 25, to prevent oscillation of the basket, but these straps are not an important feature of the invention and may be dispensed with when desired. The numeral 34 indicates a hood applied to the basket and which also constitutes no part of the present invention.

The baskets, with their supporting bases will frequently be sold for use as complete devices and without any especial adaptation for application to the running gear and, in such arrangement, the upper spreader rim sections 22, instead of having the narrow ribs 22^a, may be provided with wider bulged portions 22^b that will engage between the upper hooks 29 of the standards 27 to prevent lateral slipping of the basket in respect to the standards.

In actual practice, this improved basket with its supporting base has been found to be a very convenient device. As preferably designed, it can be supported as a sort of hammock not only from the posts or uprights of a running gear, thereby forming a complete baby carriage, but may be supported from suitable hooks or straps applied within an

automobile body and, moreover, may be used independently of such suspending supports when resting on a floor or other fixed support. In its use as a device supported from its own base, it affords the best kind of a crib or bed for babies or small children. It will be understood that the drawings illustrate the preferred form or invention, but the same is capable of modification as to details of construction and arrangement of parts all within the scope of the invention herein broadly disclosed and claimed.

What we claim is:

1. A support for use with a collapsible baby basket having upper and lower portions reinforced by spreader means, comprising a base having standards detachably engageable with the upper spreader means at the ends of the basket and supporting said basket with its bottom above said base, said base having abutments limiting the upward movement of said standards toward each other and putting the same under stress when engaged to support said basket, said standards being pivotally movable outward and downward and foldable into the plane of said base.

2. A support for use with a collapsible baby basket having a marginal spreader rim in its bottom and in the end portions of its top having marginal spreader rim sections, comprising a supporting base formed from a rod bent into oblong form with upstanding abutments at the front and rear portions thereof, and standards pivoted on said base-forming rod and movable upward and inward against said abutments, said standards at their upper ends having hooks detachably engageable with intermediate portions of the upper spreader rim sections of said basket.

3. A support for use with a collapsible baby basket having a marginal spreader rim in its bottom and in the end portions of its top having marginal spreader rim sections, comprising a supporting base formed from a rod bent into oblong form with upstanding abutments at the front and rear portions thereof, and standards pivoted on said base-forming rod and movable upward and inward against said abutments, said standards at their upper ends having hooks detachably engageable with intermediate portions of the upper spreader rim sections of said basket, the said parts being so arranged that said standards, in their engagement to support said basket, will cause the intermediate side portions of said base-forming rod to spring downward and the hooks of said standards to be held in interlocking engagement with said upper spreader rim sections.

4. A support for use with a baby basket provided with reinforcing spreader means at its front and rear upper ends, comprising a supporting base, and standards adapted to detachably connect said base to the front and

rear reinforcing spreader means of said basket and support the basket with its bottom above said base, said standards being pivoted to said base, said base having abutments against which said standards will be pressed, while engaging said spreader means, with sufficient force to spring the base structure and maintain an outward stretching pressure between opposite ends of said basket.

5. A support for baby baskets comprising a base-forming rod bent into oblong form with upstanding abutments at its front and rear end portions, and standards pivoted to the base-forming rod and movable pivotally from an inoperative position in the plane of and within said base, downward, outward and upward to an operative position against said abutments.

6. A support for baskets comprising a base-forming rod bent to form a continuous base member with upstanding abutments at opposed points, and standards pivoted to said base and movable pivotally from an operative position wherein said standards are approximately in the plane of and within said base downward, outward and upward against said abutments.

7. A support for baby baskets comprising an oblong base formed at its opposite end portions with upstanding abutments and standards pivoted to said base and movable from an inoperative position approximately in the plane of said base to an upstanding position against said abutments.

In testimony whereof we affix our signatures.

JOHN A. LEVERING.
